ABSTRACT OF THE DISCLOSURE

A waveguide formed by an inner conductor and flat rectangular outer conductors for heating web shaped non-metallic materials in an electromagnetic radiation field established between the inner conductor and the outer conductors. The inner conductor is folded inside the outer conductors and connected at each end to respective inner conductors of coaxial lines having outer conductors to which the first-mentioned waveguide outer conductors are connected.

This invention relates to a device for heating web shaped non-metallic materials or bulk goods in an electromagnetic radiation field.

It is known to heat web shaped non-metallic materials, for example textile or paper webs, by passing them through a meander shaped waveguide. A device serving for such a purpose has been proposed which is constructed from a rectangular waveguide bent into meander shape, the waveguide being slotted to a width of several millimeters on its wide side, along the axis of symmetry. Web shaped goods to be heated are guided through the slot. The bending of the electromagnetic wave through 180° takes place in rounded or angular knee portions, the disturbance regions of which are compensated by known compensation means, for example pins and apertures, in order to avoid standing waves along the line. As a rule, the slots terminate in front of the waveguide knee portions, where as a result of these transition regions, supplementary reflections occur which have to be compensated. It is very difficult to exclude all reflections over a wide band in this device. Standing waves of low amplitude, particularly when treating synthetic plastics and performing similar steps, where temperature ranges of a few degrees centigrade have to be adhered to, lead to non-uniformities in heating of the material. Moreover, with slot widths of more than 5 mm., radiation losses and couplings between adjacent waveguides occur, which can lead to standing waves. As a result of this, thick webs cannot be heated.

In most processes which can be performed using meander shaped waveguides, the steam which occurs has to be extracted from the waveguide. Slots in the waveguide wall are disturbance regions, which can cause reflections. Moreover, as a result of the complicated construction of the previously proposed device, satisfactory ventilation can be achieved only with considerable difficulties. Also, the mechanical construction of such a device is very difficult and consequently expensive, for large web widths.

The present invention consists in a device for heating web shaped non-metallic materials or bulk goods in an electromagnetic radiation field, comprising a waveguide formed by an inner conductor and flat rectangular outer conductors, the inner conductor and the outer conductors enclosing the treatment space between them, the inner conductor being periodically bent so as to have a meander shaped, sinusoidal or trapezoidal form the amplitude of which is smaller than the width of the outer conductors, the ends of the inner conductor being guided out from between the outer conductors and being connected to inner

2

conductors of coaxial lines the outer conductors of which are electrically conductively connected with the outer conductors.

Such a device is very simple to construct. Reflections at the bends of the inner conductor can by suitable shaping be kept to such small values that practically on a progressive wave is propagated. Radiation losses, such as occur with meander shaped waveguides, cannot occur. The heating of thick webs presents no difficulties since the entire intermediate space between the inner and outer conductor is available for passage of the goods. More especially, the device of the invention has great advantages as a result of the possibility of double conveyance at the two sides of the inner conductor. Moreover, ventilation of the interior is simple, if the outer conductor is made of a perforated plate. A plurality of these devices may be arranged perpendicularly alongside each other and the web shaped material, for example textile webs printed on one side, can be fed in a freely suspended manner through the individual devices, over reversing rollers.

The device of the invention is suitable not only for heating web shaped materials, but more particularly with a perpendicular arrangement, is also suitable for heating bulk goods. With such an arrangement, the inner conductor is covered on both sides with plates of low loss dielectric so that the bulk material slides between smooth walls.

In order to make the invention clearly understood, reference will now be made to the accompanying drawings which are given by way of example and in which:

FIG. 1 is a perspective view of a device of the invention;

FIG. 2 is a longitudinal section through a horizontally arranged device according to FIG. 1, for web shaped materials;

FIG. 3 is a longitudinal section through a perpendicularly arranged device according to FIG. 1; and

FIG. 4 is a longitudinal section through a perpendicularly arranged device for bulk goods.

40 In FIG. 1, an inner conductor 1 which is periodically bent in a sinusoidal shape is arranged with equal spacings between two flat outer guide plates 2, which are connected at two oppositely lying sides in each case by a metal wall 3 so that a common tubular outer guide 2, 3 with a narrow rectangular cross section is produced which encloses all of the convolutions of the inner conductor 1. The material to be heated, for example web shaped material 4 (see FIG. 3) runs through the device in the Z direction 5. The amplitude of convolution of the inner conductor 1 is smaller than the overall width of the outer conductor 2, 3. Both ends 8, 9 of the inner conductor 1 merge into coaxial lines 10, 11. A microwave generator 12 is connected to the coaxial line 10, and the other coaxial line 11, if the inner conductor 1 does not terminate at the side wall 3, is provided with a termination load 13 which receives the non-absorbed electromagnetic energy.

The two intermediate spaces between the inner conductor 1 and the external conductor plates 2, 2 in each case form a chamber 14 of the treatment space for the material to be treated.

A web 4 to be heated, is for example guided through both chambers 14 on both sides of the inner conductor 1.

45 In FIG. 2, the mounting 15 for the inner conductor 1 can be seen. The mounting 15 is of low loss synthetic plastics material and compensates the disturbance regions of the 180° bends 16. The outer conductor 2, 3 extends at the inlet and outlet openings 17, 18 beyond the inner conductor 1 by several wavelengths, in order that the openings 17, 18 are free of radiation as a result of sufficiently high damping of the waveguide.

In FIG. 3 a plurality of devices according to FIG. 1 are arranged vertically alongside each other, the web

shaped material being guided therethrough in a freely suspended manner, over reversing rollers 19.

A similar arrangement to FIG. 3 is shown in FIG. 4. This device can be used for heating bulk goods 20. For this purpose, the inner conductor 1 is covered on both sides by synthetic plastics plates 21 of low loss material, in order to provide chambers 14 with smooth walls 22.

What I claim is:

1. A device for heating web shaped non-metallic materials or bulk goods in an electromagnetic radiation field, comprising a waveguide formed by an inner conductor between two flat rectangular outer conductors, the inner conductor and the outer conductors enclosing the treatment space between them, the inner conductor being periodically bent so as to have a meander shaped, sinuous or trapezium form the amplitude of which is smaller than the width of the outer conductors, the ends of the inner conductor being guided out from between the outer conductors and being connected to inner conductors of coaxial lines the outer conductors of which are electrically conductively connected with the outer conductors.

2. A device as claimed in claim 1, wherein edges of the outer conductors which run parallel to the axis of symmetry of the periodically bent inner conductor are electrically conductively connected with each other by metal plates in which transition openings are provided for the outwardly extending coaxial lines.

3. A device as claimed in claim 1, wherein the outer conductors extend by a plurality of wavelengths beyond the inner conductor in the direction of the axis of symmetry of the periodically bent inner conductor.

4. A device as claimed in claim 1, wherein the outer conductors consist of perforated plates.

5. A device as claimed in claim 1, wherein the inner conductor is covered on its sides facing the outer conductors with plates of low loss synthetic plastics material.

6. A device as claimed in claim 1, wherein the inner conductor is surrounded by a layer of dielectric material.

7. Apparatus for heating web-shaped non-metallic materials and bulk goods in an electromagnetic radiation field comprising,

5 first and second generally parallel outer conductors, a meander-shaped inner conductor insulatedly separated from and between said first and second outer conductors,

10 first and second coaxial waveguides each having an outer conductor connected with said first and second outer conductors and an inner conductor coupled to a respective end of said meander-shaped inner conductor, the coaxial waveguide inner conductors thereby being intercoupled by said meander-shaped inner conductor,

20 20. Apparatus in accordance with claim 7 wherein both regions between said meander-shaped inner conductor and respective ones of said first and second outer conductors comprise heating chambers for the material to be treated.

25 25. Apparatus in accordance with claim 7 wherein said first and second outer conductors comprise perforated plates.
